BOBBIN SPINNING MACHINE FOR THE
MANUFACTURE OF ARTIFICIAL SILK

Walter Zinselmeyer, Remscheid-Lenne, Germany, assignor to firm Barmer Maschinenfabrik A.-G., Wuppertal-Oberbarmen, Germany

Application December 27, 1930, Serial No. 505,157,
and in Germany January 30, 1930

8 Claims. (Cl. 18—8)

In the hitherto known bobbin spinning machines for the manufacture of artificial silk the bobbins are arranged in a row disposed in the longitudinal direction of the machine. These machines have the disadvantage, that the spinning process is interrupted for a definite period while exchanging the fully wound bobbins for empty ones. This not only diminishes the output of the machines but also interferes with the uniformity of the silk.

For this reason, continuously working machines have been proposed wherein for one spinning nozzle or one group of spinning nozzles two bobbins are provided which are mounted on a tiltable carrier extending longitudinally of the machine. The bobbins are arranged on spindles which are parallel to the bobbin carrier and which engage in gear wheels of the driving shaft. They are adapted to be alternately brought into operative and inoperative position. Reciprocating thread guides are provided to wind the threads in cross windings on the spools. Each of the spindles may be pivotally mounted and may be swung out to replace the fully wound bobbin by an empty one. Another construction provides a dead space for the exchanging of the fully wound bobbins. These machines, however, require large longitudinal space, are rather complicated, and difficult in operation. Moreover, the threads must be torn off by hand and the broken ends laid on the empty bobbins.

Another machine has been proposed wherein each two bobbins together with a spinning nozzle are combined to form a spinning element and only one bobbin is being driven at any time. Each pair of bobbins is in this case tiltable about a shaft disposed transversely of the machine. When a bobbin is fully wound, it is swung out of the working position, the empty bobbin is simultaneously swung into the working position, the thread broken off by hand and the other end attached to the empty bobbin. The full bobbins are then replaced by empty ones, whilst the spinning process is in progress, whereby the process is rendered continuous.

Due to the duplicated arrangement of the bobbins on shafts disposed transversely of the machine, the overall length of the machine is undesirably large and therefore uneconomical.

The object of the present invention is a bobbin spinning machine for the manufacture of artificial silk which is such that the above mentioned disadvantages are avoided. This machine is of the kind in which a plurality of bobbins are provided for each spinning nozzle, of which one only is always in the working position while another one is being replaced by an empty bobbin. The characteristic feature of the invention consists in arranging the bobbins in opposition in two or more rows on a carrier member mounted in a tiltable manner to extend longitudinally of the machine. As soon as the bobbins in the operative position have been filled, the bobbins are simultaneously swung around by rotation of the carrier member.

Thread transferers are mounted on the carrier member and, during the movement of the latter, take hold of the individual threads, lift them off the full bobbins and deflect them on to the empty bobbins. The thread transferers are provided, for this purpose, with a rest which receives the thread when the carrier member is tilted, and with an inclined thread deflector, along which the thread slides on to the displaced empty bobbin. The transferred thread comes against the periphery of a thread cutting disc on the bobbin holder and is there cut off.

It is preferable to provide the machine with a device, which ensures that only the bobbins disposed in the operative position are driven whereas the other bobbins remain stationary. A separate driving gear is therefore provided for each row of bobbins which can be thrown into or out of engagement as desired. This is preferably effected by means of an alternate-coupling device so constructed that, upon the throwing of the one row of bobbins into gear, the other bobbins are simultaneously disengaged and come to rest. This alternate-coupling device may also be operated automatically by the swinging of the carrier member.

If groups of more than two bobbins be mounted on the carrier member, the arrangement may be modified so that, at any one time, only one row of bobbins is stationary while the bobbins of the other rows are being rotated, so that, for example, of these latter rows one may be being wound and another, for instance, may be being washed with liquids, while rotating in a trough, adjusta-

ble as regards height, provided on the machine for this purpose.

It is of advantage in the tending of such a machine to have it constructed non-symmetrically. 5 Hereby is avoided the disadvantage that the one or other row of bobbins, whether it be that disposed in the operative position or that disposed in the at rest position, is disposed in the interior of the machine and is in consequence difficult of 10 access. It has been found advantageous to provide the spinning bath and the thread guides, together with the row of bobbins disposed in the operative position, on the one side of the machine, whilst the row of bobbins in the at rest 15 position is arranged at the rear side of the machine. It is much easier and simpler to replace the fully wound bobbins from this side of the machine, as they are stationary and easily accessible. The separate drive for each row of bobbins 20 may be effected for example, by means of two shafts mounted in the tiltable carrier member and driving, through worm gearing, the stub shafts upon which the bobbins are mounted. A train of gearing is provided for each of the individual driving shafts to allow of the attainment 25 of the automatic drive, these trains being alternately connected with the driving shaft through idle gear wheels and a rotary wedge clutch.

The machine according to the present invention 30 exhibits all the advantages of the hitherto known types of machines. By reason of the novel arrangement of the bobbins the machine only has a small overall length in the longitudinal direction, which is the direction of primary importance 35 as regards space requirements. Furthermore the operation of the machine is continuous due to the employment of a plurality of bobbins and the arrangement thereof on a tiltable carrier member. The employment of thread transferers and 40 thread cutting discs allows of a mechanical and automatic transference of the thread during the exchange of the bobbins. In addition, the transference is effected at all bobbins simultaneously whereby uniformity of the thickness of the winding 45 is ensured. It is of advantage furthermore that the bobbins to be replaced are not disposed on the same side of the machine as the bobbins being wound, whereby negligence in the tending 50 of the machine does not give rise to the danger, as hitherto, of an interruption in the spinning process.

The separate drive of each row of bobbins has the advantage that the bobbin holders which are thrown out of action can be stopped so that the 55 fully wound bobbins may be easily removed and replaced by empty bobbins. The automatic regulation of the drive by means of an alternate-coupling device, which is actuated by the displacement of the carrier member, ensures operation without 60 loss of time and material.

In order more particularly to describe the nature of this invention, reference will be made to the accompanying drawings, wherein:—

Fig. 1 shows a one-sided, unsymmetrical machine with the thread-transferers and a separate drive for each row of bobbins, in sectional side elevation;

Fig. 2 is a front elevation thereof, and

Fig. 3 is a plan view of the bobbin arrangement and thread transferers.

Fig. 4 is a detail perspective view showing the tiltable carrier in one position, the winding of one bobbin having just been completed.

Fig. 5 is a similar view showing the first step in

the movement of the tilting member for bringing an empty bobbin into winding position.

Fig. 6 is a similar view showing the final step in a movement of the tilting carrier with the empty bobbin in thread cutting position and ready for winding. 80

The machine frame 1 has rotatably mounted thereon, in bearings 19 arranged one on each side in the longitudinal direction, a tubular carrier member 7, in the interior of which are mounted the bobbin driving shafts 6 and 6'. The bobbins 10, 10' are mounted on the carrier member in two opposed overhanging rows. The bobbins are formed as sleeves which are pushed on bobbin holders comprising hollow cylindrical bodies 11, 12 and stub shafts 8, 9 secured thereto, respectively, these stub shafts 8, 9 being journaled in the wall of the carrier member 7 and projecting within the latter to receive worm wheels 13, 13', respectively, which mesh with worm wheels 35, 35' on the driving shafts 6 and 6' respectively. On the inner end of the hollow cylindrical bodies 11 and 12 are mounted respective discs 15 and 15' each having a peripheral cutting edge formed with a number of notches shown respectively 100 at 14 and 14'. Thread-transferers 17 and 17' each bent a number of times, are provided for each bobbin, being formed to provide a rest 16 or 16' on the one side and to an inclined diverting member 18 and 18', running out to the bobbin 105 axis, on the other side. In the precipitating bath trough are arranged the usual spinning nozzles 2 from which the threads 3 are led to the bobbins 10 by way of the thread guides 5.

Above the row of bobbins 10 is disposed the 110 oscillating spindle 20 for the thread guides 5 this spindle receiving its motion from an eccentric or heart cam 22 through a lever 23. The driving shafts 6', 6 are provided at their ends with spur gear wheels 24, 25 respectively. These gear wheels 24, 25 mesh with gear wheels 26, 27 mounted on shafts 28, 29 on the carrier member 7. On these shafts are loosely mounted gear wheels 30, 31 which are continuously driven by the gear wheel 34 on the driving shaft. In order 120 to drive the one or other of the driving shafts 6, 6' the gear wheel 30 or 31 is alternatively coupled by means of a rotary wedge coupling 32 or 33 with the shaft 28 or 29, respectively, so that the drive is transmitted through the gear- 125 ing 26, 24 or 27, 25 respectively, to one of the driving shafts 6', or 6. The engagement and disengagement of the couplings 32, 33 may be effected either by hand or automatically by means of the belt guiding member which is displaced 130 along conical bodies so as to make the speed of rotation of the driving shafts 6', 6 agree with the changing circumference of the bobbins.

The method of operation of the machine will now be explained with reference to Figs. 1, 4, 5, and 6. During the winding of the bobbins 10 the empty bobbins 10' are fixed in place. After the bobbins are fully wound, the carrier member is rotated around its longitudinal axis in the bearing 19, through 180° so that now the bobbins 10' are being wound, whilst the full bobbins 10 are shifted to the other side for changing purposes.

During this rotation of the carrier member 7 the thread 3 first comes to bear on the rest 145 16 of the thread transferer 17, then moves along the diverting member 18, which inclines towards the bobbin axis, until it is caught in the notches 14' in the cutting disc 15' on the holder 12 supporting the bobbin 10', and broken there- 150

by, whereby the full bobbin 10 is freed from the thread 3 whilst the other end of the thread 3 is gripped by and wound upon the bobbin 10', which has meanwhile attained to its front position, the full bobbins 10 now disposed in the rear position being capable of being replaced by empty bobbins. In this manner the transferring of the thread from the full bobbin to the empty bobbin is effected automatically and without interruption of the spinning operation.

As the carrier member is being rotated the bobbin 10' is set in motion due to the fact that the gear wheel 30 is coupled with the shaft 28 by the engagement of the coupling 32, so that the shaft 6' and, consequently, the bobbins 10' are set in motion through the gear wheels 26, 24. After the rotation of the carrier member has been effected, the coupling 33 is disengaged to cause the gear wheel 31 again to run freely on the shaft 29, thus allowing the bobbin shaft 6 and, therefore, the bobbins 10 also, to come to rest. Whilst the bobbins 10' are being wound, the replacement of the full bobbins 10 by empty ones may now be effected.

What I claim is:

1. A bobbin spinning machine for the manufacture of artificial silk, comprising a tiltable carrier member extending longitudinally of the machine, several rows of rotatable shafts arranged transversely on said carrier member, one row of shafts corresponding in number to the number of spinning nozzles, and provided with bobbin holders, a plurality of thread transmitters, arranged in rows on said carrier member, each thread transmitter being provided with a rest and a diverting member and adapted to catch the thread from the periphery of one bobbin and to guide it to the periphery of another bobbin when the carrier member is tilted, means for cutting off the transferred thread arranged on said shafts, and a plurality of thread guides, corresponding in number to the spinning nozzles.

2. A bobbin spinning machine for the manufacture of artificial silk comprising a plurality of spinning nozzles, reciprocating thread guides, corresponding in number to the number of said nozzles, a plurality of bobbin holders, arranged in rows, each spinning nozzle and each thread guide corresponding to a plurality of bobbin holders, said bobbin holders being fixed on rotatable shafts, these shafts being transversely arranged on a carrier member extending longitudinally of the machine, and a plurality of thread transmitters corresponding in number to the number of bobbin holders, and arranged on said carrier member, each thread transmitter being provided with a rest and a diverting member and adapted to guide the thread from the bobbin of one row to the corresponding bobbin of another row, cutting off discs arranged in connection with said bobbin holders on the shafts.

3. In a bobbin spinning machine for the manufacture of artificial silk, a rotatable carrier member, a plurality of bobbin supporting shafts projecting at right angles to said members in spaced angular relation around the axis of the member to move into and out of winding position as the member is rotated, means to rotate said member by a step-by-step movement to bring the bobbin shafts successively into winding position, a thread guide positioned in spaced relation to the winding position of said bobbin shafts, and thread transmitters carried by the carrier member and movable therewith in a path between the thread guide and winding position of the bobbin shafts.

4. In a bobbin spinning machine for the manufacture of artificial silk, a rotatable carrier member, a plurality of bobbin supporting shafts projecting at right angles to said member in spaced angular relation around the axis of the member to move into and out of winding position as the member is rotated, means to rotate said member by a step-by-step movement to bring the bobbin shafts successively into winding position, a thread guide positioned in spaced relation to the winding position of said bobbin shafts, thread transmitters carried by the carrier member and movable therewith in a path between the thread guide and winding position of the bobbin shafts, and a bobbin on each shaft provided at one end with a cutting disk for cutting the transferred thread off adjacent the empty bobbin upon rotation of the carrier member.

5. In a bobbin spinning machine for the manufacture of artificial silk, a rotatable carrier member, a plurality of bobbin supporting shafts projecting at right angles to said member in spaced angular relation around the axis of the member to move into and out of winding position as the member is rotated, means to rotate said member by a step-by-step movement to bring the bobbin shafts successively into winding position, a thread guide positioned in spaced relation to the winding position of said bobbin shafts, thread transmitters carried by the carrier member and movable therewith in a path between the thread guide and winding position of the bobbin shafts, and means to selectively drive the bobbin shafts operable upon each shaft upon movement of the shaft into winding position and freeing the shaft for rest upon movement out of winding position.

6. In a bobbin spinning machine for the manufacture of artificial silk, a rotatable hollow carrier member, a plurality of bobbin supporting shafts projecting at right angles to said member in spaced angular relation around the axis of the member, to move into and out of winding position as the member is rotated, means to rotate said member by a step-by-step movement to bring the bobbin shafts successively into winding position, a thread guide positioned in spaced relation to the winding position of said bobbin shaft, thread transmitters carried by the carrier member and movable therewith in a path between the thread guide and winding position of the bobbin shafts, a driving shaft for each of the bobbin shafts, and extending in the hollow carrier member, and gearing connecting each driving shaft to a respective bobbin shaft.

7. In a bobbin spinning machine for the manufacture of artificial silk, a rotatable hollow carrier member, a plurality of bobbin supporting shafts projecting at right angles to said member in spaced angular relation around the axis of the member to move into and out of winding position as the member is rotated, means to rotate said member by a step-by-step movement to bring the bobbin shafts successively into winding position, a thread guide positioned in spaced relation to the winding position of said bobbin shaft, thread transmitters carried by the carrier member and movable therewith in a path between the thread guide and winding position of the bobbin shafts, a driving shaft for each of the bobbin shafts and extending into the hollow carrier member, gearing connecting each driving shaft to a respective bobbin shaft, and means to selectively actuate said driving shafts as the respective bobbin shafts are moved into winding position.

8. In a bobbin spinning machine for the manufacture of artificial silk, a rotatable carrier member, a plurality of bobbin supporting shafts projecting at right angles to said member in spaced angular relation around the axis of the member to move into and out of winding position as the member is rotated, means to rotate said member by a step-by-step movement to bring the bobbin shafts successively into winding position, a

thread guide positioned in spaced relation to the winding position of said bobbin shafts, and thread transmitters carried by the carrier member and movable therewith in a path between the thread guide and winding position of the bobbin shafts, each of said transmitters being provided with a thread engaging portion and a thread diverting portion.
